UNITED STATES PATENT OFFICE

166,580

MULTIPURPOSE TABLE

Harriet M. Thompson, Ridgefield, Conn.

Application February 5, 1952, Serial No. 18,397

Term of patent 14 years

(Cl. D33—14)

To all whom it may concern:

Be it known that I, Harriet M. Thompson, a citizen of the United States of America, residing at Ridgefield, in the county of Fairfield and State of Connecticut, have invented a new, original, and ornamental Design for Multi-Purpose Tables, of which the following is a specification, reference being had to the accompanying drawings, forming a part hereof.

Fig. 1 is an isometric view of a multi-purpose table embodying my new design, in which the table is shown with its leaves in a fully raised position;

Fig. 2 is an isometric view of the multi-purpose table with the leaves in a lowered position;

Fig. 3 is an end elevational view on a reduced scale of the table in the position shown in Fig. 2, and

Fig. 4 is a side elevational view on a reduced scale of the table in the position shown in Fig. 1.

I claim:

The ornamental design for a multi-purpose table, as shown.

HARRIET M. THOMPSON.
